2,584,131

PYRROLIDYL THIOESTERS

James H. Hunter, Kalamazoo, Mich., assignor to
The Upjohn Company, Kalamazoo, Mich., a
corporation of Michigan

No Drawing. Application June 6, 1949,
Serial No. 97,483

11 Claims. (Cl. 260—313)

1

This invention relates to pyrrolidyl-1 and (alkylpyrrolidyl-1) alkanthiol esters, particularly to esters of certain alpha, alpha-di-substituted acetic acids and to their acid addition salts.

The esters of this invention have the formula:

wherein R is a member of the group consisting of aryl, aralkyl, cycloalkyl, and cycloalkenyl radicals, R' is a member of the group consisting of alkyl, aralkyl, aryl, cycloalkyl and cycloalkenyl radicals, R'' is a member of the group consisting of pyrrolidyl-1 and lower-alkyl-substituted pyrrolidyl-1 radicals and wherein n is a member of the group consisting of the integers 2, 3, and 4.

The esters are usually oily liquids, readily soluble in most common organic solvents, but insoluble in water. The acid addition salts, such as the hydrochloride, sulfate, hydrobromide, nitrate, acetate, tartrate, succinate, and citrate are generally crystalline solids with well-defined melting points and are readily soluble in cold water, methanol, or ethanol; moderately soluble in ethyl acetate; and, insoluble in common aliphatic, cycloaliphatic and aromatic hydrocarbon solvents.

Members of this new group of compounds have been prepared and found to have value as antispasmodics and as intermediates for the preparation of more complex organic molecules. These compounds have exhibited most desirable antispasmodic properties, having the combined effect of papaverine and atropine. Atropine is considered to be a neurotropic agent, acting upon the smooth muscle tissue to overcome spasm originated by or produced through the autonomic nervous system. Papaverine, an opium alkaloid, is considered to be a muscletropic agent capable of acting on smooth muscle tissues to relieve spasm intrinsic in the muscle tissues themselves.

In clinical practice it is not always possible to determine which type of spasm is present. Furthermore, both types may be present simultaneously, presenting a situation in which an antispasmodic effective against only a single type is, obviously, of limited utility. The compounds with which the present invention is concerned possess muscletropic and neurotropic activity and upon administration, exhibit a dual antispasmodic effectiveness of sufficient degree to render them useful in treating either of the previously mentioned types of spasm, or both simultaneously, if both should be present.

2

The free basic esters of the invention can be prepared readily by reacting an acid chloride having the formula:

with a pyrrolidyl alkanthiol having the formula:

wherein R, R', R'' and n have the values given previously. It is to be here noted that it is possible to have thio-esters having the sulfur in two possible places. Those esters having the formula

are called thion esters and those having the formula

are called thiol esters. This invention is limited to thiolacetates, as hereinafter described. The corresponding acid bromides can also be used, if desired, although the preparation of the compounds of the present invention will be described with particular reference to the acid chlorides. The acid chlorides mentioned can be prepared readily and in excellent yield by treating the corresponding acid with thionyl chloride for a period of from one to several hours. The reaction can be carried out conveniently at the refluxing temperature of the mixture. An excess of thionyl chloride is usually employed and the excess subsequently removed by distillation under a reduced pressure, leaving the acid chloride as a residue, which is generally sufficiently pure for use without further purification, but which can be fractionally distilled, if further purity is desired. Acid bromides can be prepared in a similar manner using thionyl bromide.

The pyrrolidyl alkane thiols used in preparing the esters of the invention can be prepared from the corresponding alkanol according to the following reactions:

55 wherein R'' has the value given.

The intermediate pyrrolidylalkylisothiouronium chloride hydrochlorides are stable crystalline compounds which can be isolated readily and crystallized from ethanol. The hydrolysis of the isothiouronium chloride hydrochlorides is carried out in an oxygen-free atmosphere, as the resulting pyrrolidylalkanths are oxidized to the disulfide by atmospheric oxygen. For this reason, it is preferred to use the solution formed by the hydrolysis of the isothiouronium salts for the preparation of its esters, rather than attempting to isolate and purify the unstable thiol. The pyrrolidyl alkyl chlorides, some of them described and claimed in copending application Serial 773,521, filed September 11, 1947, now abandoned, are readily prepared by the reaction of thionyl chloride on pyrrolidylalkanol hydrochlorides.

The pyrrolidyl alkanols used in preparing the pyrrolidyl alkylthiols can be prepared in several ways. Thus, a haloalkanol can be reacted with pyrrolidine or with an alkyl pyrrolidine and the desired pyrrolidyl alkanol obtained. In certain instances, it is advantageous to first condense pyrrolidine or an alkyl pyrrolidine with a halo-ketone, an ester of a saturated halo-aliphatic acid, or an ester of an alpha-beta unsaturated aliphatic acid to form an ester of a pyrrolidyl aliphatic acid or a pyrrolidyl ketone. In other instances, it may be advantageous to condense an amino alcohol with succinic acid to form an N-hydroxyalkyl succinimide or with a gamma keto aliphatic acid to form an N-hydroxyalkylpyrrolidone. The carbonyl groups of these compounds may then be easily reduced with lithium aluminum hydride in absolute ether to the desired pyrrolidyl and alkylpyrrolidyl alkanols. Other pyrrolidyl alkanols may be prepared by condensing a pyrrolidine with formaldehyde and an aliphatic aldehyde to give an N-pyrrolidyl-aldehyde, which is readily reduced with aluminum isopropoxide in isopropyl alcohol to the desired pyrrolidyl or alkylpyrrolidyl alkanols. Detailed preparations of pyrrolidyl and alkylpyrrolidyl alkanols by these methods are given hereinafter.

The reaction of an acid chloride and of a pyrrolidyl alkanthiol can be carried out conveniently by mixing the two substances together, preferably in the presence of an inert diluent, such as anhydrous xylene. Reaction usually occurs at ordinary temperatures and can be accelerated and carried substantially to completion by finally refluxing the mixture for about thirty minutes or longer. Upon allowing the reaction mixture to cool, the hydrochloride of the basic ester generally crystallizes and can be separated from any inert diluent by filtration. The free ester can be recovered and purified by dissolving the crude hydrochloride in water, extracting the solution with a suitable solvent, e. g., ether, to remove any remaining inert diluent or any other water insoluble substances, alkalizing the solution with sodium carbonate, extracting with ether or other suitable organic liquid, and distilling to volatilize the solvent. The basic esters can be distilled under reduced pressure to purify them further, if desired.

Salts of the basic esters with acids, such as, with hydrochloric, hydrobromic, hydroiodic, sulfuric, phosphoric, acetic, succinic, propionic, benzoic, citric, lactic, and other acids, can be readily prepared by allowing the ester to react with the acid in a suitable solvent, such as alcohol, or a mixture of alcohol and ethyl acetate.

Upon distilling the solvent, the salt remains as a residue, which can be recrystallized from alcohol, or other suitable organic liquid. A mixture of ethyl alcohol and ethyl acetate is particularly suitable, in certain instances, for the recrystallization. Salts with inorganic acids, especially with hydrochloric acid or with citric acid, have particularly well-defined crystalline structures. Certain of the polybasic acids, such as citric acid, combine with the amino esters in equimolecular proportions to form the monoamine salts.

Only one of the two substituents on the alpha carbon atom of the aliphatic acid component of the esters of the invention can be an alkyl radical, and either one or both of the two substituents can be aryl, aralkyl, cycloalkyl, or cycloalkenyl radicals. Alkyl radicals which can be present as one of the substituents on the alpha carbon atom can have either a straight or branched carbon chain and include, for example, methyl, ethyl, propyl, isopropyl, n-butyl, isobutyl, tertiary-butyl, hexyl, dodecyl, et cetera. Generally speaking, an alkyl radical containing not more than 12 carbon atoms is preferred, although the compounds of the present invention are not to be limited in this respect. Other substituent radicals, which can be present on the alpha carbon atom of the acid component include, among many others, phenyl, orthotolyl, para-tolyl, xylol, benzyl, methyl-benzyl, diphenylmethyl, naphthyl, cyclohexyl, methylcyclohexyl, propylcyclohexyl, cyclohexenyl, methylcyclohexenyl, cyclopentyl, and cyclopentenyl radicals. The pyrrolidyl alkanths used in preparing esters of the invention can be a pyrrolidyl-ethanethiol, a pyrrolidyl-propanthiol or a pyrrolidyl-butanthiol. The carbon chain of the alkylene group $—C_nH_{2n}—$, can be either straight or branched. The pyrrolidine ring can be either unsubstituted or it may contain one or more lower-alkyl substituents, such as methyl, ethyl, propyl, isopropyl, butyl, secondary-butyl, tertiary-butyl, pentyl, isopentyl, et cetera. It is to be understood that I do not intend to limit myself to pyrrolidyl rings containing only one lower-alkyl substituent on a ring carbon atom of the pyrrolidyl ring, but intend to include all lower-alkyl substituted pyrrolidyl rings. By lower-alkyl as used in this specification and the appended claims is intended any alkyl group having from one to five carbon atoms. The pyrrolidine ring is attached to the alkylene group through the nitrogen atom.

The esters of this invention may be named in at least two ways. For example, the ester:

may be designated as 1-[2-methyl-2-(2'-methylpyrrolidyl-1')-propyl]-alpha,alpha-diphenylthiolacetate, or as 2-methyl-2-(2-methylpyrrolidyl-1)-1-propyl alpha,alpha-diphenylthiolacetate. The second system is used throughout this specification and the appended claims.

Certain procedures by which the compounds of the present invention may be prepared are apparent from the following examples which are given by way of illustration and are not to be construed as limiting.

PREPARATION OF PYRROLIDYL ALKANOLS

Preparation 1.—Ethyl-alpha-(pyrrolidyl-1)-propiionate

To a stirred solution of 181 grams of ethyl-alpha-bromopropionate in 200 milliliters of ben-

zene, 148 grams of pyrrolidine was added at a substantially uniform rate over a period of one hour. The reaction was quite vigorous causing the solvent to boil. When all of the pyrrolidine had been added, the solution was boiled under reflux for an additional hour, cooled, poured into about 300 milliliters of ice-water, acidified with dilute aqueous hydrochloric acid to a pH of about 2, and the resulting two layers separated. The aqueous layer was washed with ether, made strongly alkaline with cold aqueous sodium hydroxide, and extracted four times with 200-milliliter portions of ether. The ether extracts were combined, the solvent removed and the residue distilled under a reduced pressure of about 12 millimeters of mercury absolute. There was thus obtained 156.7 grams (91.5 percent of the theoretical yield) of ethyl alpha-(pyrrolidyl-1)-propionate, boiling at 84 degrees centigrade at a pressure of 12 millimeters of mercury absolute.

Preparation 2.—2-(pyrrolidyl-1)-propanol-1

A mixture of 7.6 grams of lithium aluminum hydride and 250 milliliters of dry ether was prepared and 61.7 grams of ethyl alpha-(pyrrolidyl-1)-propionate added to the mixture slowly enough to cause gentle refluxing of the ether. The mixture was then allowed to stand for a few minutes without cooling and 20 milliliters of water added dropwise. The mixture was then cooled by adding ice and the mixture acidified with hydrochloric acid to a pH of about 2. The aqueous layer was separated, washed with ether and then rendered strongly basic with solid sodium hydroxide. The basic solution was then extracted repeatedly with ether, the ethereal extracts combined and dried with anhydrous potassium carbonate. The ether was then removed by evaporation and the residual oil fractionally distilled. There was thus obtained 38.1 grams of 2-(pyrrolidyl-1)-propanol-1, boiling at 80 degrees centigrade at a pressure of 11 millimeters of mercury absolute, and having an index of refraction, n_D^{25} , of 1.4758.

Preparation 3

Following substantially the procedure given in Preparations 1 and 2, the following alcohols were prepared:

1. 2-methyl-3-(pyrrolidyl-1)-propanol-1, boiling at 91 degrees centigrade at a pressure of 12 millimeters of mercury absolute; n_D^{25} of 1.4620.

2. 3-(pyrrolidyl-1)-butanol-1, boiling at 114 degrees centigrade at a pressure of 21 millimeters of mercury absolute; n_D^{25} of 1.4742.

3. 3-(pyrrolidyl-1)-butanol-2, boiling at 79 degrees centigrade at a pressure of 13 millimeters of mercury absolute; n_D^{25} of 1.4610.

4. 4-(pyrrolidyl-1)-butanol-2, boiling at 87 degrees centigrade at a pressure of 13 millimeters of mercury absolute; n_D^{25} of 1.4611.

Preparation 4.—3-(pyrrolidyl-1)-propanol-1

A mixture was prepared consisting of 50.7 grams of sodium hydroxide, 45.7 grams of water and 60.5 grams of pyrrolidine. The mixture was stirred vigorously and 100 grams of 3-chloropropanol-1 was added to the mixture at a substantially uniform rate over a period of one-half hour. The temperature rose gradually and was maintained between about 75 and 100 degrees centigrade during the addition. The mixture was then stirred for an additional thirty minutes and finally allowed to stand for several hours. Solid sodium hydroxide was then added until the mixture was saturated and the oily layer which

formed was separated. The aqueous layer was extracted with benzene and the combined oily layer and benzene extract fractionally distilled. A fraction was collected consisting of 65.5 grams of 3-(pyrrolidyl-1)-propanol-1, boiling at 115 degrees centigrade at a pressure of 45 millimeters of mercury absolute, index of refraction, n_D^{25} of 1.4701.

Preparation 5

Following substantially the procedure given in Preparation 4,4-(pyrrolidyl-1)-butanol-1, boiling at 113 degrees centigrade at a pressure of 12 millimeters of mercury, n_D^{25} of 1.4705, was prepared from pyrrolidine and 4-chlorobutanol-1.

Preparation 6.—2-methyl-2-(pyrrolidyl-1)-propanol-1

A mixture of 44.6 grams of 2-amino-2-methylpropanol-1, 108 grams of tetramethylene dibromide and 200 milliliters of toluene was boiled under reflux for three hours, 84 grams of sodium bicarbonate added and the refluxing continued for an additional fifteen hours. The mixture was then cooled, 80 milliliters of 50 percent aqueous sodium hydroxide added, the organic layer removed, sufficient water added to dissolve the salt and the aqueous solution extracted continuously for nine hours. The organic extracts were combined, dried over anhydrous potassium carbonate and distilled. The distillate, melting at 27.5 degrees centigrade, was dissolved in dilute acid and treated with sodium nitrite to remove any secondary amine. After extracting with ether, the aqueous solution was made basic with sodium hydroxide and extracted three times with 100-milliliter portions of ether. The ether solutions were combined, dried, the ether removed and the residue distilled under a reduced pressure of about 12 millimeters of mercury absolute. There was thus obtained 54 grams (75.5 percent of the theoretical yield) of 2-methyl-2-(pyrrolidyl-1)-propanol-1, boiling at 87 degrees centigrade at a pressure of 12 millimeters of mercury absolute, index of refraction, n_D^{20} of 1.4720, freezing point 30 degrees centigrade.

Preparation 7.—1-(2-hydroxyethyl)-5-methylpyrrolidone-2

A suspension of 0.2 gram of platinum oxide catalyst in 25 milliliters of absolute ethanol was reduced to platinum and then a solution of 34.8 grams of levulinic acid and 37.8 grams of ethanolamine in 75 milliliters of absolute alcohol added. The mixture hydrogenated at about 50 pounds' pressure and room temperature for four hours, at which time the theoretical amount of hydrogen had been consumed. After the catalyst and solvent had been removed, the residue was fractionally distilled. There was thus obtained 42.5 grams (100 percent of the theoretical yield) of 1-(2-hydroxyethyl)-5-methylpyrrolidone-2, boiling at 167 degrees centigrade at a pressure of 12 millimeters of mercury absolute, index of refraction, n_D^{20} of 1.4900.

Preparation 8.—2-(2-methylpyrrolidyl)-1-ethanol

By a procedure similar to that described in Preparation 2, fifty-one grams of 1-(2-hydroxyethyl)-5-methylpyrrolidone-2 was reduced with 18 grams of lithium aluminum hydride in 400 milliliters of ether. Fractional distillation yielded 35 grams (76 percent of the theoretical yield) 75 of 2-(2-methylpyrrolidyl-1)-ethanol, boiling at

81 degrees centigrade at a pressure of 16 millimeters of mercury absolute, index of refraction, n_D^{25} of 1.4680.

Preparation 9

By a procedure similar to that described in Preparations 7 and 8, the following compounds were prepared:

1. 2-(2,3-dimethylpyrrolidyl-1)-ethanol, boiling at 86 degrees centigrade at a pressure of 13 milliliters of mercury absolute, n_D^{25} of 1.4661.

2. 3-(2-methylpyrrolidyl-1)-propanol-1, boiling at 100 degrees centigrade at a pressure of 18 millimeters of mercury absolute, n_D^{25} of 1.4672.

Preparation 10.—N-(2-hydroxyethyl)-alpha-methylsuccinimide

A mixture of 66 grams of alpha-methylsuccinic acid and 73.4 grams of monoethanolamine was heated by means of an oil bath, the temperature gradually rising to 260 degrees centigrade until distillation stopped. The residue was distilled under a reduced pressure of less than one millimeter of mercury absolute, to obtain a viscous oil which upon fractional distillation yielded 67.8 grams (86.4 percent of the theoretical yield) of N-(2-hydroxyethyl)-alpha-methylsuccinimide, boiling at 102 degrees centigrade at a pressure of 0.01 millimeter of mercury absolute, refractive index of 1.4970.

Preparation 11.—2-(3-methylpyrrolidyl-1)-ethanol

By a procedure similar to that described in Preparation 2, 62.8 grams of N-(2-hydroxyethyl)-alpha-methylsuccinimide was reduced with 30 grams of lithium aluminum hydride. Upon fractional distillation there was obtained 35 grams (68.1 percent of the theoretical yield) of 2-(3-methylpyrrolidyl-1)-ethanol, boiling at 105 degrees centigrade at a pressure of 45 millimeters of mercury absolute, refractive index, n_D^{25} of 1.4640.

Preparation 12

By a procedure similar to that described in Preparations 10 and 11, the following alcohols were prepared:

1. 2-(3,3-dimethylpyrrolidyl-1)-ethanol, boiling at 81 degrees centigrade at a pressure of 13 millimeters of mercury absolute; n_D^{25} of 1.4580.

2. 2-(3,4-dimethylpyrrolidyl-1)-ethanol, boiling at 86 degrees centigrade at a pressure of 12 millimeters of mercury absolute; n_D^{25} of 1.4594.

3. 2-(2,4,4-trimethylpyrrolidyl-1)-ethanol, boiling at 84 degrees centigrade at a pressure of 14 millimeters of mercury absolute; n_D^{25} of 1.4535.

PREPARATION OF PYRROLIDYL ALKYL HALIDES

Preparation 13.—2-(2-methylpyrrolidyl-1)-ethyl chloride hydrochloride

To a cooled solution of 51.8 grams of 2-(2-methylpyrrolidyl-1)-ethanol in 200 milliliters of dry benzene, 16 grams of anhydrous hydrogen chloride was added, followed by the slow addition of 36.3 milliliters of thionyl chloride. The mixture was then heated on a steam bath for two hours during which time the desired chloride-hydrochloride began to crystallize. Upon cooling, there was obtained a quantitative yield of 2-(2-methylpyrrolidyl-1)-ethyl chloride hydrochloride, which, after washing with benzene and ether, melted at 183.5-185 degrees centigrade. Recrystallization from isopropanol raised the melting point to 184-185.5 degrees centigrade.

Preparation 14

Following substantially the procedure given in Preparation 13, the following pyrrolidyl-alkyl chloride hydrochlorides were prepared:

1. 2-(pyrrolidyl-1)-propyl chloride hydrochloride, melting at 150-163 degrees centigrade.

2. 4-(pyrrolidyl-1)-n-butyl chloride hydrochloride, melting at 111-113 degrees centigrade.

3. 2-methyl-3-(pyrrolidyl-1)-n-propyl chloride hydrochloride, melting at 164.5-165.5 degrees centigrade.

In a like manner, other pyrrolidyl alkyl chloride hydrochlorides can be prepared from the alcohols described in the preceding preparations as well as those described in J. Am. Chem. Soc. 70, 3101 (1948), and a copending application, Serial 773,521, filed September 11, 1947.

PREPARATION OF ISOTHIOURONIUM CHLORIDES

Preparation 15.—2-(methylpyrrolidyl-1)-ethyl isothiouronium chloride hydrochloride

A solution of 46 grams of 2-(2-methylpyrrolidyl-1)-ethyl chloride hydrochloride and 19 grams of thiourea in 50 milliliters of ethanol was boiled under reflux for twenty hours on a steam bath.

Upon cooling, crystals separated which were filtered, washed with ethanol and acetone, recrystallized from 250 milliliters of ethanol and dried. There was thus obtained 43.3 grams (95 percent of the theoretical yield) of 2-(2-methylpyrrolidyl-1)-ethyl isothiouronium chloride hydrochloride, melting at 216-218 degrees centigrade.

Preparation 16

Following substantially the procedure given in Preparation 15, the following pyrrolidyl-alkyl-isothiouronium chloride hydrochlorides were prepared:

1. 2-(pyrrolidyl-1)-ethyl-isothiouronium chloride hydrochloride, melting at 174-175 degrees centigrade.

2. 2-(pyrrolidyl-1)-propyl-isothiouronium chloride hydrochloride, melting at 184.5-186 degrees centigrade.

3. 4-(pyrrolidyl-1)-n-butyl-isothiouronium chloride hydrochloride, melting at 168-169.5 degrees centigrade.

4. 2-methyl-3-(pyrrolidyl-1)-n-propyl-isothiouronium chloride hydrochloride, melting at 215-216.5 degrees centigrade.

In a like manner, other pyrrolidyl-alkyl-isothiouronium chloride hydrochlorides can be prepared from the pyrrolidyl alkyl chloride hydrochlorides obtained from the alcohols of the previous preparations.

PREPARATION OF THIO ALCOHOLS

Preparation 17.—2-(2-methylpyrrolidyl-1)-ethanethiol

A solution of 16.9 grams of 2-(2-methylpyrrolidyl-1)-ethyl isothiouronium chloride hydrochloride in 30 milliliters of water and a solution of 5.3 grams of sodium hydroxide in 20 milliliters of water were mixed in a container at room temperature. The flask was attached to an apparatus adapted for continuous extraction with ether, the air displaced with nitrogen and the mixture then extracted with peroxide-free ether for six hours.

The ethereal solution of 2-(2-methylpyrrolidyl-1)-ethanethiol thus obtained was dried with anhydrous calcium sulfate and used directly in Example 1.

In a like manner, the following pyrrolidyl-alkan thiols and alkylpyrrolidylalkan thiols can be prepared by hydrolysis of the corresponding iso thiouronium chloride hydrochloride:

- 2-(pyrrolidyl-1)-ethan thiol
- 2-(3-methylpyrrolidyl-1)-ethan thiol
- 2-(2,3-dimethylpyrrolidyl-1)-ethan thiol
- 2-(2,4-dimethylpyrrolidyl-1)-ethan thiol
- 2-(3,3-dimethylpyrrolidyl-1)-ethan thiol
- 2-(2,5-dimethylpyrrolidyl-1)-ethan thiol
- 2-(2,4,4-trimethylpyrrolidyl-1)-ethan thiol
- 2-(2-ethylpyrrolidyl)-ethan thiol
- 2-(pyrrolidyl-1)-propan thiol-1
- 3-(pyrrolidyl-1)-propan thiol-1
- 2-methyl-2-(pyrrolidyl-1)-propan thiol-1
- 3-(2-methylpyrrolidyl-1)-propan thiol-1
- 2-methyl-3-(pyrrolidyl-1)-propan thiol-1
- 1-(pyrrolidyl-1)-propan thiol-2
- 1-(2,4-dimethylpyrrolidyl-1)-propan thiol-2
- 1-(2,5-dimethylpyrrolidyl-1)-propan thiol-2
- 3-(pyrrolidyl-1)-butan thiol-1
- 4-(pyrrolidyl-1)-butan thiol-1
- 3-(pyrrolidyl-1)-butan thiol-2
- 1-(pyrrolidyl-1)-butan thiol-3

PREPARATION OF THIO-ESTERS

Example 2.—(2-methylpyrrolidyl-1)-ethyl alpha-phenyl-alpha-(Δ^2 -cyclopentenyl)-thiol acetate

The dry ethereal extract containing 2-(2-methylpyrrolidyl-1)-ethan thiol from Preparation 17 was added to a solution of 13.3 grams of alpha - phenyl - alpha - (Δ^2 - cyclopentenyl) - acetyl chloride contained in 50 milliliters of anhydrous benzene. The reaction mixture, which rapidly separated into two layers, was heated under reflux for two hours, poured into a mixture of dilute aqueous hydrochloric acid and the layers separated. The organic layer was extracted with water, the aqueous solutions combined and extracted once with ether. The aqueous solution was made basic with sodium hydroxide, and the 2 - (2 - methylpyrrolidyl - 1) - ethyl alpha - phenyl - alpha - (Δ^2 - cyclopentenyl) - thiol acetate extracted with ether. The ether extract was washed with water and dried.

2-(2-methylpyrrolidyl-1)-ethyl alpha-phenyl-alpha-(Δ^2 -cyclopentenyl)-thiol acetate hydrochloride was prepared by passing dry hydrogen chloride into a portion of the above ethereal solution of the free base. The salt, after crystallization from ethyl acetate, melted at 111-115 degrees centigrade.

Analysis:
Calculated for $C_{20}H_{28}ClNO_2$: N 3.83 S 8.76 Cl 9.69.
Found: 3.61 8.83 9.64.

In a like manner the following esters and their salts were prepared:

1. 2 - (pyrrolidyl-1) - ethyl alpha, alpha - di phenyl-thiolacetate hydrochloride, melting at 140-141 degrees centigrade.

Analysis:
Calculated for $C_{20}H_{24}ClNO_2$: N 3.87 S 8.86 Cl 9.80.
Found: 4.09 9.02 9.63.

2. 2-(pyrrolidyl-1)-ethyl alpha-cyclopentyl alpha-n-propylthiolacetate, boiling at 107 degrees centigrade at a pressure of 0.025 millimeter of mercury absolute. Hydrochloride, melting at 146-148 degrees centigrade.

Analysis:
Calculated for $C_{18}H_{30}ClNO_2$: S 10.02 Cl 11.08.
Found: 9.89 11.09.

3. 2-(pyrrolidyl-1) - 1-propyl alpha-phenyl-alpha-isobutylthiolacetate citrate, melting at 158-158.5 degrees centigrade.

Analysis:
Calculated for $C_{25}H_{37}NO_3S$: N 2.74 S 6.27.
Found: 2.91 6.31.

4. 4-(pyrrolidyl-1)-butyl alpha-phenyl-alpha- Δ^2 -cyclohexenylthiolacetate hydrochloride, melting at 133-134 degrees centigrade.

10 *Analysis:*
Calculated for $C_{22}H_{32}ClNO_2$: N 3.56 S 8.14 Cl 9.00.
Found: 3.69 8.14 9.13.

5. 2-methyl-3-(pyrrolidyl-1) - 1-propyl alpha-phenyl alpha-cyclopentylthiolacetate, boiling at

15 160-170 degrees centigrade at a pressure of 0.05 millimeter of mercury absolute. Hydrochloride, melting at 121-124 degrees centigrade.

Analysis:
Calculated for $C_{21}H_{34}ClNO_2$: N 3.67 S 8.39 Cl 9.28.
Found: 3.77 8.36 9.46.

20 6. 2-(2-methylpyrrolidyl-1)-ethyl alpha- Δ^2 -cyclopentenyl-alpha-n-propylthiolacetate citrate was prepared by adding a slight excess of citric acid in ethanol to an ethyl acetate solution of the free ester. The citrate melted at 100-102 degrees centigrade.

Analysis:
Calculated for $C_{23}H_{37}NO_3S$: N 2.87 S 6.58.
Found: 2.90 6.79.

30 In a manner similar to that of the above Example, the following esters of various pyrrolidylalkan thiols and alkylpyrrolidyl alkan thiols can be prepared as well as acid addition salts thereof.

2-(pyrrolidyl-1)-ethyl alpha, alpha-diphenylthiolacetate

2-(2,3-dimethylpyrrolidyl-1)-ethyl alpha, alpha-diphenylthiolacetate

2-(3,4-dimethylpyrrolidyl-1)-ethyl alpha, alpha-diphenylthiolacetate

40 2-(2,4,4-trimethylpyrrolidyl-1) - ethyl alpha, alpha-diphenylthiolacetate

2-(2-ethylpyrrolidyl-1)-ethyl alpha, alpha-diphenylthiolacetate

2 - methyl - 2 - (pyrrolidyl - 1) - 1 - propyl alpha, alpha-diphenylthiolacetate

45 2 - methyl - 3 - (pyrrolidyl - 1) - 1 - propyl alpha, alpha-diphenylthiolacetate

1 - (2,5 - dimethylpyrrolidyl - 1) - 2 - propyl alpha, alpha-diphenylthiolacetate

50 1 - (pyrrolidyl - 1) - 3 - butyl alpha, alpha-diphenylthiolacetate

1 - (pyrrolidyl - 1) - 4 - pentyl alpha, alpha-diphenylthiolacetate

2-(pyrrolidyl-1)-ethyl alpha-phenyl alpha- Δ^2 -cyclopentenylthiolacetate

2 - (2,4,4 - trimethylpyrrolidyl - 1) - ethyl alpha-phenyl alpha- Δ^2 -cyclopentylthiolacetate

2 - (2 - ethylpyrrolidyl - 1) - ethyl alpha-phenyl alpha- Δ^2 -cyclopentylthiolacetate

60 3-(pyrrolidyl-1)-1-propyl alpha-phenyl alpha- Δ^2 -cyclohexenylthiolacetate

2-(pyrrolidyl-1)-ethyl alpha-phenyl alpha-cyclopentylthiolacetate

2 - (2,4,4 - trimethylpyrrolidyl - 1) - ethyl alpha-phenyl alpha-cyclopentylthiolacetate

Various modifications may be made in the compounds of the present invention without departing from the spirit or scope thereof, and it is to be understood that I limit myself only as defined in the appended claims.

I claim:

1. A member of the group consisting of (a) esters having the formula:

wherein R is a member of the group consisting of aryl, aralkyl, cycloalkyl and cycloalkenyl radicals, R' is a member of the group consisting of alkyl, aryl aralkyl, cycloalkyl and cycloalkenyl radicals, R'' is a member of the group consisting of pyrrolidyl-1 and lower-alkyl-substituted pyrrolidyl-1 radicals and n is a member of the group consisting of the integers 2, 3, and 4, and (b) acid addition salts thereof.

2. Acid addition salts of esters having the formula:

wherein R is aryl, R' is cycloalkenyl, R'' is a lower-alkyl-substituted pyrrolidyl-1 radical, and n is the integer 2.

3. Acid addition salts of esters having the formula:

where R and R' are aryl, R'' is pyrrolidyl-1, and n is the integer 2.

4. Acid addition salts of esters having the formula:

wherein R is aryl, R' is alkyl, R'' is pyrrolidyl-1 n is the integer 3.

5. Acid addition salts of esters having the formula:

wherein R is aryl, R' is cycloalkenyl, R'' is pyrrolidyl-1 and n is the integer 4.

6. Acid addition salts of esters having the formula:

wherein R is aryl, R' is cycloalkyl, R'' is pyrrolidyl-1 and n is the integer 4.

7. 2-(2-methylpyrrolidyl-1)-ethyl alpha-phenyl-alpha-(Δ^2 -cyclopentenyl)-thiolacetate hydrochloride.

8. 2-(pyrrolidyl-1)-ethyl alpha, alpha-diphenyl-thiolacetate hydrochloride.

9. 2-(pyrrolidyl-1)-1-propyl alpha-phenyl-alpha-isobutylthiolacetate citrate.

10. 4-(pyrrolidyl-1)-butyl alpha-phenyl-alpha- Δ^2 -cyclohexenylthiolacetate hydrochloride.

11. 2-methyl-3-(pyrrolidyl-1)-1-propyl alpha-phenyl-alpha-cyclopentylthiolacetate hydrochloride.

JAMES H. HUNTER.
